[57] **CLAIM**

The ornamental design for a bottle, as shown and described.

DESCRIPTION

FIG. 1 is an isometric view of a first embodiment of the bottle of the present invention;

FIG. 2 is a magnified bottom view of the bottle of FIG. 1; FIG. 3 is a front view of the bottle of FIG. 1, the rear view is the same;

FIG. 4 is a right side view of the bottle of FIG. 1, the left side view is the same;

FIG. 5 is a top view of the bottle of FIG. 1;

FIG. 6 is an isometric view of an alternate embodiment of the bottle of the present invention;

FIG. 7 is a magnified bottom view of the bottle of FIG. 6; FIG. 8 is a left side view of the bottle of FIG. 6;

FIG. 9 is a front view of the bottle of FIG. 6;

FIG. 10 is a back view of the bottle of FIG. 6;

FIG. 11 is a right side view of the bottle of FIG. 6;

FIG. 12 is a top view of the bottle of FIG. 6;

FIG. 13 is an isometric view of a second alternate embodiment of the bottle of the present invention;

FIG. 14 is a magnified bottom view of the bottle of FIG. 13; FIG. 15 is a left side view of the bottle of FIG. 13;

FIG. 16 is a front side view of the bottle of FIG. 13;

FIG. 17 is a back view of the bottle of FIG. 13;

FIG. 18 is a right side view of the bottle of FIG. 13; and,

FIG. 19 is a top view of the bottle of FIG. 13.
